United States Patent Office.

EMERY ANDREWS AND WILLIAM TUCKER, OF PORTLAND, MAINE.

Letters Patent No. 92,415, dated July 13, 1869.

IMPROVEMENT IN MATCH-MACHINE.

The Schedule referred to in these Letters Patent and making part of the same.

To all whom it may concern:

Be it known that we, EMERY ANDREWS and WILLIAM TUCKER, of Portland, in the county of Cumberland, and State of Maine, have invented a new and useful Improved Match-Machine; and we hereby declare the following to be a full, clear, and exact description thereof, which will enable others to make and use our invention, reference being had to the accompanying drawings, forming part of this specification, in which—

Figure 1, plate 1, is a side elevation of our invention.

Figure 2, a detail of the stop-motion.

Figure 3, a detail top view of the clutch, with the lever and slide for operating the same.

Figure 4, is a front view of the slotted disk attached to the ratchet-wheel of the stop-motion.

Figure 5 is a detached sectional plan of the crank-plate and cross-head.

Figure 1, plate 2, is a top plan of our machine.

Figure 2 is a detail of the stat-feeding apparatus.

Figure 3, a detached side elevation of the same.

Figure 4 is a detached side elevation of a section of the feed-plate.

Figure 5, a detached end elevation of the toothed end of the feed-plate, and the grooved bed in which it runs.

This invention relates to certain improvements in a machine for making match-splints, for which Letters Patent were granted to us, December 2, 1864, and further Letters Patent, August 27, 1867.

Our improvement consists, first, in raising the slats in the rack to be filled, and resting them on reciprocating wedges, which wedges drop one slat down on each card, as it is delivered into the rack by the operation of the feed-plates.

It further consists in feeding the rack down, by wedges, attached to a cross-head, thus dispensing with the use of the slotted feed-bar employed in our invention patented August 27, 1867.

Furthermore, our invention consists in furnishing the under side of the teeth of the feed-plate with slight projections, which run in corresponding grooves in the table, and thus keep the teeth of the feed-plate from playing in any direction.

Our invention furthermore consists in providing a ratchet-wheel with as many teeth as there are slats in the rack, the ratchet-wheel having a disk, with a slot through the edge of it, said disk being attached to the outer face of the wheel. A bar, with a wedge-shaped end, is placed in suitable guides, and held against the disk by a spring. The ratchet-wheel and disk are moved by the pawl over one tooth of the wheel, for each stroke of the cross-head; and as, by the revolution of the wheel, the slot in the disk comes opposite the bar, the bar is thrown into it by the action of the spring. By this movement of the bar, the wedge-end thereof strikes a pin on a shaft, to which a clutch is

fastened, thus moving the shaft sufficiently to throw the clutch out of gear, and so check the operation of the machine.

A particular reference to the drawings will illustrate the nature of our invention.

A is a frame, upon which the machine rests.

B is a cross-head, having a slot, *c*, on its under side, into which catches the eccentric stud *d*, said stud being mounted on the upper end of the upright driven shaft *e*.

f is the driving-wheel.

g, the driving-shaft, operating the driven shaft *e*, by the bevel-gears *h*, from which, it will be seen, a reciprocating motion is given to the cross-head.

The feed-plates *i i* are attached to the cross-head, as described in our patent of August 27, 1867, No. 68,144, and their action in taking cards from the hopper and driving them through knives, is also therein specified, as well as depositing the splints in the rack.

The under side of the teeth of the feed-plates *j*, extend below the under side of the plate, and are received into grooves *k*, made in the table *L*. These projections on the teeth always remain in these grooves, sliding backward and forward in them, thus stiffening the teeth, by keeping them from bending either way, and guiding each tooth to its proper place in the knives.

To the cross-head *B* are attached the swinging rods *m m*, the ends of which are hinged on the ends of the tappet-levers *n n*.

Sliding rods *o o* are attached to the tappets by means of a pin, *p*, fastened in the rods, and extending into slots *q q*, in the tappets.

The ends of the sliding rods are connected by means of cross-bars *r s*, of which *r* is rigidly fastened, and *s* made adjustable, so as to move on the rods, and be held by any suitable device, such as a set-screw or key.

By means of the swinging rods, tappet-levers, and sliding rods, a reduced reciprocating motion, corresponding in time to the motion of the cross-head, is imparted to the cross-bars *r* and *s*.

Short wedges, *t*, are attached to the cross-bar *r*, and longer ones, *w*, to the bar *s*.

A rack, *3*, such as described in patent No. 68,144, heretofore granted to us, is placed in the machine at *W*.

The slats are slipped up on the wires, and rested on the longer wedges *w*, preparatory to starting the machine.

The points of the wedges *t* are elevated above the points of the wedges *w*, a distance equal to the thickness of one slat in the rack, and as the feed-plates advance with the cross-head, and deliver a card cut into splints on to the rack, the wedges *t t* are also advanced, and driven between the two lower slats in the rack, which are resting on the longer wedges *w*; thus these wedges *t* support all except the lowest slat in the rack.

At this point, by the operation of the machine, the wedges *w* begin to withdraw from under the slat, and

as soon as all but the lowest slat are resting on the wedges *t*, they, *w*, draw entirely out, and the lowest slat drops down on to the wedges *v*.

In the backward motion of the cross-head, &c., the shorter wedges *t* are withdrawn from under the slats, when they all drop on to the longer wedges *w*, thus being prepared for another forward motion of the cross-head, at which time another slat is dropped, and so on until the rack is filled, when it can be removed from the machine, for the purposes of dipping.

The wedges or bars *v*, are attached to the cross-head, and receive motion from it, and the under side of their ends being bevelled, they slip over the slat last dropped by the wedges *t* and *w*, and as they advance, they crowd it down, thus feeding down the rack, as described in patent No. 68,144, before alluded to.

The bar *x* has a shoulder, which rests against the edge of the disk *y*, attached to the ratchet-wheel *z*.

The bar is held against the disk by means of the spring 4.

The bar *D* has an oscillating motion imparted to it by means of the slotted piece *E*, rigidly attached to the cross-head.

This is effected by means of a pin, 6, in the slot.

A pawl, *G*, is attached to the bar *D*; and as the bar vibrates by the motion of the cross-head, it imparts an intermittent motion to the wheel and its disk.

The bevel-gear *h* is loose on its shaft, and only imparts motion to the machine when the clutch *H*, which is splined on to the shaft, is clutched into it.

When the machine is not operating, the shoulder of the bar *x* is slid into the disk, in the groove therein.

To start the machine, the gears being in motion, the bar *x* is drawn out of the groove, and the clutch slipped into the gear. As soon as one or two motions are made by the cross-head, it revolves the ratchet-wheel and disk sufficiently, so that the operator may let go of the bar *x*, and it will rest on the edge of the disk, till the

slot in the disk comes opposite the bar. The spring then throws the bar into the slot, and the end of the bar, which is wedge-shaped, strikes against the pin *k* in the shipping-shaft, and turns it enough to unclutch the gear, and the machine cannot be started, till the bar is again drawn back, and the clutch slipped and held as before.

The patent of William Gates, Jr., No. 11,860, October 31, 1854, is different from ours.

We do not claim forcing the splints forward, for the purpose of delivering them to the rack, but simply a means of keeping the feed-plate from playing in any direction, and we hereby disclaim a feeding-bar, projections, pressure-rods, gauge-block, and springs, as shown in the said patent. Neither do we claim placing a match-frame, for the purpose of being filled, in an upright frame, which has a sliding cross-piece containing a movable step, as in the patent of A. Sohn, April 18, 1854, No. 10,809.

We do not claim, broadly, stopping the machine at a desired time.

We do not claim feeding the rack down, as shown in our previous patents, December 2, 1864, and August 27, 1867.

What we claim as our invention, and desire to secure by Letters Patent, is—

1. The wedges or bars *v*, attached to the cross-head, and operating as and for the purposes described.
2. The arrangement of the ratchet-wheel *z*, cam-bar *D*, and clutch *H*, as herein described.
